UNITED STATES PATENT OFFICE

2,184,741

HIGH FREQUENCY SMELTING FURNACE

Fritz Hartmann, Dortmund, Germany, assignor to
 Kohle-und Eisenforschung G. m. b. H., Dusseldorf, Germany, a limited-liability company

Application November 17, 1938, Serial No. 240,930
 In Germany November 19, 1937

4 Claims. (Cl. 13—27)

When smelting metals in high-frequency furnaces of large capacity there exists, owing to the relatively thin walls of the crucible, the danger of the liquid metal breaking out through the 5 crucible wall. In the case of such breaking out, apart from the destruction of the coils, explosions might occur, and the liquid metal may come into contact with the cooling water.

Experience has shown, that a breaking out is 10 prepared by the formation of small cracks or crevices in the crucible wall which cracks and crevices fill with metal and spread in outward direction. It is evident that such cracks cannot be detected during the smelting.

15 In most cases the breaking out takes place so suddenly that, even if the threatening breaking out can make itself apparent in some way by external signs, there is nevertheless not enough time to cut out the furnace.

20 To counteract the danger of breaking out, it is proposed according to the invention to utilize the change of temperature of the cooling water, caused by the penetration of the hot metal into the wall of the crucible, by arranging in the 25 cooling water current temperature-influenced devices, such as thermo-electric couples, resistance coils or bimetal strips, which in the event of inadmissible rise in temperature cut out the furnace switch by means of known mechanical or electrical transmission elements. It 30 is advisable to arrange a thermo-electric couple or the like not only at the cooling water outlet but also at the cooling water inlet. Thus, it is possible to control the actual rise in temperature of the cooling water in the furnace independently of the inlet temperature of the cooling water which mostly fluctuates. If the two 35 thermo-electric couples in differential connection are jointly actuated, even a considerable increase in the sensitivity of the cut out can be 40 thereby attained so that it is possible to indicate breaking out in its inception.

Two embodiments of the invention are illustrated by way of example in the accompanying 45 drawing, in which:—

Fig. 1 is a diagrammatical view showing the arrangement of a thermo-electric couple in the cooling water inlet,

Fig. 2 is a similar view showing the arrangement of a thermo-electric couple in the inlet and another in the outlet of the cooling water.

In the drawing 1 designates a crucible in whose wall a current conducting coil 2 is embedded and is connected to a source 3 of high frequency alternating current through the con-

tacts 11 and 12. In the example illustrated the coil consists of a tube, through which the cooling water flows. The cooling water enters at 3 and passes out at 4. The electric connection of the induction furnace is effected in the usual manner over fuses 10 and a main switch 5. According to Fig. 1 the protecting device consists of a thermo-electric couple 6 which acts on a relay 7. The relay 7 in responding, closes a secondary circuit 8 to energize an electromagnet 14 to attract a detent armature 15 by which the main switch 5 is switched off through the action of a spring 16.

An indicating instrument may be used instead of the relay 7, if this instrument has in known 15 manner cut off contacts by which the secondary circuit 8 is controlled. The use of an indicating instrument instead of a relay presents the advantage that the heating process can be observed and the outflow temperature of the water can be 20 read at any time. The interposing of a secondary circuit 8 is recommended as the thermo-currents are too weak to attain the direct actuation of the main switch.

Instead of the thermo-electric couple 6, other 25 devices may be fitted according to the invention provided they can be influenced by changes in temperature. For example a resistance coil may be provided which presents the advantage that an intermediate relay between resistance coil 30 and cut out of the main switch can be dispensed with. Thermometers with cut off contacts may also be employed. By using bimetal strips as temperature influenced devices a mechanical transmission of the movement of the bimetal 35 strip under changes of temperature to the main switch may also be attained.

According to Fig. 2 thermo-electric couples are arranged one 6' in the outlet 4 and another 6 in the inlet 3 for the cooling water. The two 40 thermo-currents, in the case of differential connection, indicate the difference in the temperatures of the cooling water at the inlet and outlet points. By the differential connection on the electromagnet 7' the protecting arrangement is 45 rendered independent of temperature fluctuations of the inflowing cooling water. Furthermore, by the differential connection the sensitivity of the indication or of the adjustment of the cut out point of the main switch can be considerably increased. This is perhaps advantageous for showing 50 on an indicating instrument the relatively slight increase in temperature already at the beginning of a break out. The protecting arrangement cuts out the furnace only when the 55

difference in temperature of the water at the inlet and outlet points increases. In most cases this will take place only when the metal breaking out is already near the coil whereby electro-
5 magnet 1' will be energized sufficiently to attract its armature 17 for closing the secondary circuit 8, as in the previously described embodiment, to actuate switch 5 through the release of detent 15 by electromagnet 14 and the action of spring
10 16.

I claim:

1. In a high frequency smelting furnace, means for avoiding breaking through, comprising in combination with a crucible and an electric circuit for heating said crucible, a main switch in said circuit, a cooling water conduit surrounding said crucible, at least one heat influenced device inserted in the cooling water, arranged in said circuit and influenced by an excessive rise in 15 temperature in the cooling water circulating through said conduit, and transmission elements between said device and switch and adapted to cut out said circuit through the actuation of said switch at the influencing of said device, by an excessive rise in temperature in the cooling water.
20 2. In a high frequency smelting furnace of the nature set forth in claim 1, two heat influenced
25

devices in the circuit, a differential relay connected to both of said devices and cooperatively connected to the main switch.

3. In a high frequency smelting furnace, means for avoiding breaking through, comprising in combination with a crucible and an electric circuit for heating said crucible, a main switch in said circuit, a cooling water conduit surrounding said crucible and connected with said circuit to constitute the induction heating coil of the furnace, at least one heat influenced device inserted in the cooling water, arranged in said circuit and influenced by an excessive rise in temperature in the cooling water circulating through said conduit, and transmission elements between said device and switch and adapted to cut out said circuit through the actuation of said switch at the influencing of said device, by an excessive rise in temperature in the cooling water.
10 15

4. In a high frequency smelting furnace of 20 the nature set forth in claim 3, two heat influenced devices in the circuit, one inserted in the inlet and one in the outlet for the cooling water, and a differential relay connected to both of said devices and cooperatively connected to 25 the main switch.

FRITZ HARTMANN.
